UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC-LAMP SOCKET.

1,251,739.

Specification of Letters Patent. Patented Jan. 1, 1918.

Application filed December 9, 1914. Serial No. 876,200.

To all whom it may concern:

Be it known that I, REUBEN B. BENJAMIN, a citizen of the United States, residing at Chicago, in the county of Cook and State of Illinois, have invented new and useful Improvements in Electric-Lamp Sockets, of which the following is a full, clear, concise, and exact description, reference being had to the accompanying drawing, forming 10 a part of this specification.

My invention relates to electric lamp sockets, and has particular reference, first, to improvements in the casing whereby an unusually strong rigid support is provided 15 for the lamp, and second, to improved means for attaching the insulating base which carries the contacts to the outer casing. In devices of this class the casing is ordinarily constructed with two parts, a body portion 20 and a cap; the cap being secured to the conduit or fixture and the body portion being attached to the cap. The disadvantage of such a construction is that where heavy shades are carried by the socket the parts 25 of the casing are liable to become separated from each other, the body portion becoming loosened and falling with the shade or being left suspended by the leading in wires.

In the device herein described and shown 30 in the drawings I so construct the body portion of the casing that it extends to and is secured upon the conduit or fixture or upon a bushing which is secured on the conduit or fixture. I also provide means for rigidly securing the shade in position by which 35 it is attached directly to the lower edge of the casing without the use of a separate attaching ring as ordinarily used.

In the accompanying drawings, in which 40 I have illustrated several embodiments of my invention;

Figure 1 is an axial section substantially on the line 1—1 of Fig. 2, of a lamp socket showing the manner in which the threaded 45 contact shell and the insulating base are secured within the casing;

Fig. 2 is an axial section on the line 2—2 of Fig. 1 showing the electrical connections between the leading in wires and the center 50 and shell contacts;

Fig. 3 is a section on the line 3—3 of Fig. 1 showing the manner in which the split washer is secured in the casing;

Fig. 4 is a bottom view of the socket showing the relative position of the screws 55 for securing the parts together;

Fig. 5 is a plan view of the insulating base which carries the binding screws;

Fig. 6 is a perspective view of one of the nuts by which the insulating base is secured 60 to the split washer;

Fig. 7 is an axial section of a modified form of my device in which the casing is provided with a threaded portion for engagement with a shade or shade holder, and 65 showing the means for securing the insulating base in the casing;

Fig. 8 is a section on the line 8—8 of Fig. 7;

Fig. 9 is a section on the line 9—9 of Fig. 70 10, showing the electrical connections between the leading in wires and the center and shell contacts;

Fig. 10 is a section on the line 10—10 of Fig. 9 showing the relative positions of the 75 binding screws and the screws which secure the base in position;

Fig. 11 is an axial section showing still another modification of my device and showing the means by which the insulating base 80 is secured to the casing;

Fig. 12 is a section on the line 12—12 of Fig. 11; and

Fig. 13 is an elevation of a modified form of casing provided with a husk and shade 85 holding portion.

Referring now to the drawing in detail, and first to the modification of Figs. 1 to 6, the socket comprises a casing indicated in general by 10 which is secured to a bushing 90 11 which may be screwed onto a conduit or fixture carrying the leading in wires. Secured within the casing 10 is an insulating base 12 to which is secured a screw threaded contact 13 and an insulating cup 14 of 95 fiber or other suitable material. The lower portion of the casing 10 is provided with an annular bead 15 for the purpose of retaining a shade holder in position. The upper portion of the casing 10 has an annular lead 16 in which is seated a split washer 17 of insulating material such as fiber. The casing 10 has formed integral therewith a cap portion 18 having an inwardly extending flange 19 over the edge of which the bushing 11 is flanged as at 20. The bushing 11

is threaded internally as at 21 for engagement with the conduit or fixture. A portion of the bead 16 may be forced inwardly as at 22 between the ends of the split washer 17 to hold the latter in position.

The washer 17 is provided with a pair of openings 23 having four flat sides 24 and four rounded portions 25 into which openings fit nuts 26 having a lower portion 27 which fits within the openings 23 and having a squared upper portion 28, the corners 29 of which over-hang said openings to prevent the nuts from being drawn downwardly through the openings. These nuts are formed from square stock which is chamfered off as at 30 to fit the openings in the washer. The insulating base 12 is provided with a pair of openings 31 therethrough, each of which opens at its upper end into a recess 32 in which the lower end 27 of the nut 26 extends. Screws 33 extend through each of the openings 31 and engage the nuts 26 to hold the base in position.

It is to be noted that the thickness of the washer plus the depth of the recess 32 should not exceed the length of the lower portion 27 of the nut in order to prevent any possibility of drawing the nut up so tightly as to mutilate the fiber washer.

The insulating base 12 has a central extension 34 forming a support for the center contact 35 and preventing any possibility of the center contact being forced into engagement with the shell contact. One end 35 of the center contact 35 is seated in a recess 36 in the base 12 being secured therein by means of a screw 37 extending through an opening in the base and engaging the binding plate 38 which is located within a recess 39 in the upper face of the base 12. A binding screw 40 engages the binding plate to hold the conductor in engagement therewith. The insulating base 12 also has a recess 41 in its upper face in which is seated a binding plate 42 in which is threaded a binding screw 43. A screw 44 extends through the opening 45 in the base 12 and engages the binding plate 42 to hold the latter in position on the base. This screw 44 also serves to assist in holding the threaded shell contact and the insulating cup in position on the insulating base 12 as hereinafter described in detail. The threaded shell contact 13 has an inwardly extending flange 47 having openings 48 therein through which the screws 33 extend to hold the shell in place on the base 12. The threaded shell contact has an opening 48 through which the screw 44 extends, which also assists in holding the shell in position. The threaded contact shell also has a central opening 49 to accommodate the extension 34 on the base 12. The fiber cup 14 has an inwardly extending flange 51 which is clamped between the flange 47 and the base 12 to hold the cup

in position. A fiber washer 52 is provided between the washer 17 and the cap portion 18 to insulate the nuts 26 from the casing 10.

In assembling the device of this modification the washer 52 is first slipped into place 70 in the casing after which the split washer 17 is forced upwardly into the casing until it can expand into the bead 16. The base 12 having the leading in wires and the contacts secured thereto is then slipped into place 75 in the casing and the screws 33 are screwed into the nuts 26 to hold the base in position in the casing.

In the modification of Figs. 7, 8, 9 and 10 reference character 53 indicates a cup shaped 80 casing having an opening 54 in its upper end through which extends a bushing 55 through which the leading in wires are brought to the binding screws. An insulating base 56 is secured within the casing 85 and carries the threaded shell contact 57 and the fiber cup 58 which insulates the threaded contact from the casing. The lower edge of the casing 58 has a threaded portion 59 formed integral therewith for engagement with the threaded portion of a lamp shade or shade holder 60. The insulating base 56 is secured in place within the casing by means of screws 61 extending through openings 62 in the casing and into recesses 90 63 in the insulating base. The base 56 is provided with a central extension 64 forming a rest for the center contact 65, the end 66 of which is secured in a recess 67 in the base 56 by means of a hollow rivet or eyelet 68 100 which also extends through an opening in the binding plate 69 to which the binding screw 70 is secured. The threaded contact 57 has at its upper end an inwardly extending flange 71 having an opening through 105 which the screw 72 extends into engagement with the binding plate 73 with which the binding screw 74 engages. The fiber cup 58 has at its upper end an inwardly extending flange 75 which is clamped between the 110 flange 71 and the base 56.

In assembling the device of this modification the base 56 having secured thereto the leading in wires and contacts and fiber cup is inserted in place in the casing 53 after 115 which the screws 61 are threaded into the casing so as to extend into the recesses 63.

In the modification of Figs. 11 and 12 the insulating base 76 is secured in place in the cup shaped casing 77 by means of a 120 screw 78 having its head located in a recess 79 in the base 76 and extending through an opening 80 in said base into threaded engagement with a lug 81 secured within the casing 77 by being riveted over as shown at 125 82. The fiber insulating cup 83 has an inwardly extending flange 84 at its upper end which is held in place between the threaded shell contact 85 and the insulating base 76. In this modification it will be noted that 130

the securing screw 78 is not electrically connected with the threaded contact 83 so that the lug 81 need not be of insulating material.

5 In Fig. 13 I have shown a modified form of casing provided with a husk portion 86 and a shade holder portion 87, both of which are formed integral with the casing which incloses the insulating base and threaded 10 shell contact.

While I have shown various means for securing the insulating base within the casing and have shown casings of various forms it is obvious that the different forms of 15 securing means may be used interchangeably with the different forms of casings.

Having thus described my invention what I claim as new and desire to secure by Letters Patent is:—

26 1. An electric lamp socket including an insulating base, a shell contact supported by said base, a casing forming a housing for said base and shell, said casing having a flange integral therewith adjacent said base 25 and on the opposite side of said base from said shell, and means for securing said base within said casing, and including a screw having its head located within said shell.

2. An electric lamp socket including an 30 insulating base, a shell contact supported by said base, a casing forming a housing for said base and shell, said casing having a flange integral therewith adjacent said base and on the opposite side of said base from 35 said shell, and means for securing said base within said casing, and including an expansible ring engaging the walls of said casing.

3. An electric lamp socket including an 40 insulating base, a shell contact supported by said base, a casing forming a housing for said base and shell, said casing having a flange integral therewith adjacent said base and on the opposite side of said base from 45 said shell, and means for securing said base within said casing, and including a screw having its head located within said shell, an expansible ring engaged by said screw engaging the walls of said casing.

50 4. An electric lamp socket including an insulating base, a shell contact supported by said base, a casing forming a housing for said base and shell, said casing having a flange integral therewith adjacent said base 55 and on the opposite side of said base from said shell, and means for securing said base within said casing, and including a split expansible ring engaging the walls of said casing.

60 5. An electric lamp socket including an insulating base, a shell contact supported by said base, a casing forming a housing for

said base and shell, said casing having a flange integral therewith adjacent said base and on the opposite side of said base from 65 said shell, and means for securing said base within said casing, including an expansible ring, said casing having a groove into which said ring expands.

6. A lamp socket including an insulating 70 base, a shell contact supported by said base, a casing forming a housing for said base and shell, said casing having an inwardly extending flange integral therewith adjacent 75 said base and on the opposite side of the base from said shell, and means for securing said base within said casing and for securing said shell to said base, comprising a screw extending through said shell and base, and having its head within said shell. 80

7. A lamp socket including an insulating base, a shell contact supported by said base, a casing forming a housing for said base and shell, said casing having an inwardly extending flange integral therewith adjacent 85 said base and on the opposite side of the base from said shell, and means for securing said base within said casing and for securing said shell to said base, comprising a screw extending through said shell and base, and having its head within said shell, and an expansible ring with which said screw engages, said casing having a groove into which said ring expands.

8. An electric lamp socket including an 90 insulating base, a shell contact supported by said base, a casing forming a housing for said base and shell, said casing having a flange integral therewith adjacent said base and on the opposite side of said base from 95 said shell, and means for securing said base within said casing, and including a split expansible ring engaging the walls of said casing, said casing having a projection extending between the separated ends of the 100 split ring to position the latter.

9. An electric lamp socket including an insulating base, a shell contact supported by said base, a casing forming a housing for said base and shell, said casing having 110 a flange integral therewith adjacent said base and on the opposite side of said base from said shell, and means for securing said base within said casing including a screw having its head accessible from within said shell.

In witness whereof, I have hereunto subscribed my name in the presence of two witnesses.

REUBEN B. BENJAMIN.
